DESIGN FOR A CHAIR

Grover J. Daly, Chicago, Ill.

Application May 28, 1934, Serial No. 51,939

Term of patent 14 years

To all whom it may concern:

Be it known that I, GROVER J. DALY, a citizen of the United States, residing at 9051 S. Loomis Street, in the city of Chicago, county of Cook, and State of Illinois, have invented a new, original, and ornamental Design for Chairs, of which the following is a specification, reference being had to the accompanying drawing, forming a part hereof:

I claim:

The ornamental design for a chair substantially as shown.

In testimony whereof, I have hereunto subscribed my name this 21st day of May, 1934.

GROVER J. DALY.
